UNITED STATES PATENT OFFICE.

RALPH R. HAMMER, OF ROSLINDALE, MASSACHUSETTS.

WATERPROOF POCKET.

Application filed March 16, 1928. Serial No. 262,192.

This invention relates to waterproof pockets and has for its object to provide a novel waterproof pocket which can be worn by bathers and in which various articles such as matches, cigarettes, powder puffs, etc. may be kept in a perfectly dry condition.

The features wherein my invention resides will be more fully hereinafter set forth and then pointed out in the appended claims.

10 In the drawings wherein I have illustrated a selected embodiment of my invention, Fig. 1 is a fragmentary view illustrating the manner in which my improved pocket may be used.

15 Fig. 2 is a perspective view of the pocket showing it open;

Fig. 3 is a rear side view of the pocket;

Fig. 4 is a horizontal section taken on substantially the line 4—4, Fig. 6 showing 20 the pocket partially closed;

Fig. 5 is a similar view showing the pocket entirely closed;

Fig. 6 is a section on the line 6—6, Fig. 5;

Fig. 7 is a section on the line 7—7, Fig. 5.

25 My improved pocket comprises a pocket member 1 which is made of waterproof material and which is shown as open at the top 2. Any suitable waterproof material may be used for making the pocket member but

30 I will preferably employ rubber for this purpose as this is not only waterproof but also more or less elastic.

The open end 2 of the pocket member is adapted to be closed in a waterproof manner through the medium of two clamping members 3 and 4 which are attached to the two opposite sides 5 and 6 of the pocket member.

35 The clamping member 4 is a strip of resilient material which is shown as riveted or otherwise secured to the side 5 of the pocket by means of suitable rivets 7. The clamping member 3 is also preferably made of metal and is secured to the side 6 of the pocket by rivets 12. The two clamping strips are so constructed that they may be detachably secured together at each end and when they are attached together the upper edges of the sides 5 and 6 of the pocket will 50 be tightly clamped between them in a manner to make a water tight joint.

40 As herein shown one end of the clamping strip 4 is provided with the lip 8 under which the end 9 of the clamping strip 3 is adapted to be entered as shown in Fig. 4. The opposite end of the clamping member

4 is provided with a spring catch 10 which is adapted to latch over the end 11 of the clamping member 3 thereby to hold the two clamping members in closed or clamping relation.

45 I have stated above that the clamping member 4 was a curved member and it is so arranged that its convex face is directed toward the clamping member 3. The clamping member 3 may be straight or if curved its curvature will be on a greater radius than the normal curvature of the clamping member 4. Said member 3 is also stiffer and less resilient than the member 4. Consequently when the end 9 of the clamping member 3 is inserted underneath the lip 8, as shown in Fig. 4, and then the two clamping members are closed together and the end 11 of the clamping member 3 is forced 75 past the catch 10 the member 4 will be straightened somewhat and its resiliency will serve to apply a firm clamping pressure to the upper portions 5, 6 of the pocket.

50 The clamping member 3 is herein shown as connected to the side 6 of the pocket member by means of suitable rivets 12 and said member is provided at its upper edge with the flange 13 which overlies the top edge of the member 4 when the clamping members are 85 closed together. The clamping member 3 is also shown as covered or enclosed in a casing 14 of rubber or some other similar yielding material and thus when the two parts are clamped together this rubber casing provides a packing between the flange 13 and the top edge of the member 4 by reason of which a water tight joint is formed at this point.

55 The clamping member 3 is also shown as deformed to provide the recess 15 on its inner face, said recess being situated to receive the heads of the rivets 7 and 12 when the clamping members are in closed relation. The advantage of this construction is that 100 since the rivet heads are located in the recess they will not prevent the two clamping members from closing tightly together.

60 It will be noted that the clamping member 3 has its lower edge 24 offset slightly 105 to form a clamping flange. When the clamping members are closed together as shown in Fig. 5 the two side walls 5 and 6 of the pocket 1 will be firmly clamped between the lower portion of the member 4 110 and the lower edge 24 of the member 3. Said side walls of the pocket will also be

firmly clamped at their upper edge between the upper edge of the member 4 and the upper portion of the clamping member 3 above the recess 15 as clearly seen in Figs. 5 6 and 7. As stated above the recess 15 is of sufficient depth to accommodate the heads of the rivets 7 and 12 so as to ensure this clamping action.

The flange 13 at the upper edge of the member 3 provides a further watertight joint between said flange and the top edge of the clamping member 4 so that when the clamping members are closed there is no possibility of any water leaking into the 15 pocket.

In order to make it sure that the flange 13 will always have a water tight engagement with the upper edge of the clamping member 4 I have provided said clamping member 3 with a lip or extension 16 which is adapted to engage the under side of the member 4 when the clamping members are closed. This lip prevents the clamping members from closing sufficiently to enable the 25 end 11 of the clamping member 3 to snap past the spring catch 10 unless the parts are so relatively positioned that the lip 16 can pass underneath the lower edge of the member 4. Consequently whenever the 30 pocket is closed the flange 13 will have a water tight engagement with the upper edge of the member 4.

A pocket having the above construction may be built into a garment or may be made 35 to be worn independently of the garment. As herein shown the pocket is designed to be carried by a belt and may thus be worn independently of a bathing suit or other garment.

40 The clamping member 4 which lies on the inside next the body is shown as provided with the U-shaped extension 17 to the lower end of which one side of the pocket member is riveted as shown at 18. This extension 45 is also provided with two loops 19 through which a belt 20 may be threaded. The extension 18 holds the pocket in shape so that when worn it will lie flatly against the body.

The pocket is absolutely water tight and 50 may be used to hold various small articles such as matches, money, either in the form of coins or bills, jewelry, toilet articles, etc. Being independent from the bathing suit it provides a pocket which can be worn by 55 any one regardless of the character of their bathing suits.

While I have illustrated herein a selected embodiment of my invention I do not wish to be limited to the constructional features 60 shown.

I claim:

1. A waterproof pocket comprising a pocket member of waterproof material open at one end and closing means for said open 65 end comprising two clamping members se-

cured to opposite sides of the pocket member at said open end, one of said clamping members being more resilient than the other and also having a curved shape with its convex face directed toward the other clamping 70 member, and means for detachably securing the members together at their ends with the convex face of the more resilient member in engagement with the other member.

2. A waterproof pocket comprising a 75 pocket member of waterproof material open at one end and closing means for said open end comprising two clamping members secured to opposite sides of the pocket member at said open end, one of said clamping members being more resilient than the other and also having a curved shape with its convex face directed toward the other clamping member, one of the clamping members having at one end a lip under which the corresponding end of the other clamping member may be received, and a spring catch device for holding the other ends of the clamping members in clamping relation. 80 85

3. A waterproof pocket comprising a 90 pocket member of waterproof material open at one end and closing means for said open end comprising two clamping members secured to opposite sides of the pocket member at said open end, one of said clamping members being more resilient than the other and also having a curved shape with its convex face directed toward the other clamping member, and means for detachably securing the members together at their ends, one of the clamping members having a flange at its 95 upper edge which overlies the upper edge of the other clamping member. 100

4. A waterproof pocket comprising a 105 pocket member of waterproof material open at one end and closing means for said open end comprising two clamping members secured to opposite sides of the pocket member at said open end, one of said clamping members being more resilient than the other and also having a curved shape with its convex face directed toward the other clamping member, means for detachably securing the members together at their ends, one of the clamping members having a flange at its 110 upper edge which overlies the upper edge of the other clamping member, and a packing interposed between said flange and said end to make a water tight joint. 115

5. A waterproof pocket comprising a 120 pocket member of waterproof material and having an open end, two clamping members secured to opposite sides of the pocket member at said open end, one of the clamping members being more resilient than the other and having a curved shape with its convex face directed toward the other clamping member, said resilient clamping member having a lip at one end under which the corresponding end of said other clamping 125 130

member may be received and having a spring catch at its other end to engage the corresponding end of the other clamping member.

5 6. A waterproof pocket comprising a pocket member of waterproof material and having an open end, two clamping members secured to opposite sides of the pocket member at said open end, one of the clamping members being more resilient than the other and having a curved shape with its convex face directed toward the other clamping member, said resilient clamping member having a lip at one end under which the corresponding end of said other clamping member may be received and having a spring catch at its other end to engage the corresponding end of the other clamping member, said other clamping member having a flange at its upper edge which overlies the top edge of the resilient clamping member, said other clamping member having a flange at its upper edge which overlies the top edge of the resilient clamping member.

7. A waterproof pocket comprising a pocket member of waterproof material and having an open end, two clamping members 25 secured to opposite sides of the pocket member at said open end, one of the clamping members being more resilient than the other and having a curved shape with its convex face directed toward the other clamping member, said resilient clamping member having a lip at one end under which the corresponding end of the other clamping member may be received and having a spring catch at its other end to engage the corresponding end of the other clamping member, 30 said other clamping member having a flange at its upper edge which overlies the top edge of the resilient clamping member, and a packing interposed between said 40 flange and said top edge.

In testimony whereof, I have signed my name to this specification.

RALPH R. HAMMER.
